UNITED STATES PATENT OFFICE.

OTTO D. JENNINGS, OF STAUNTON, VIRGINIA.

DESIGN FOR A DOLL.

Application filed August 25, 1926. Serial No. 18,870. Term of patent 14 years.

To all whom it may concern:

Be it known that I, OTTO D. JENNINGS, a resident of Staunton, county of Augusta, State of Virginia, and a citizen of the United States, have invented a new, original, and ornamental Design for Dolls, of which the following is a specification, reference being had to the accompanying drawings, forming a part thereof.

Fig. 1 of said drawings is a vertical front elevational view; Fig. 2 is a side elevational view of a doll showing my new design.

I claim:

The ornamental design for a doll as shown. In testimony whereof I hereunto affix my signature.

OTTO D. JENNINGS.
